UNITED STATES PATENT OFFICE.

MARTHA H. CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DECORATED SHEET METAL.

Application filed November 19, 1925. Serial No. 70,179.

This invention is an improvement in decorated sheet metal, and in methods of producing the same, and more particularly in the production of sheet metal especially adapted for the making of containers such as are used for toilet articles and the like.

One of the primary objects of the invention is the provision of a method of decorating sheets of metal and the like with designs, wherein selected portions of the designs are provided by the ornamental surface of the sheet.

Another object of the invention is the provision of a sheet having a suitable design thereon, wherein selected portions of the design are provided by the color tinted crystallized surface of the sheet.

Another object is the provision of a sheet having a crystallized surface providing selected portions of a design printed thereon.

To the accomplishment of the foregoing and such other objects as may hereinafter appear, the invention consists in the article, in the method and the several steps thereof, as hereinafter defined in the appended claims.

In the drawings is shown the representation of a part of a sheet, showing the various steps of the method.

In carrying out the method, a sheet of suitable material as for instance tin is provided with a so called crystallized surface, which surface is afterwards coated with a transparent coating of a suitable tint, upon which the design is printed in silhouette.

The plain surface of the sheet, indicated at 1, is first cleansed by treating with an alkali as for instance by dipping in a potash solution, or in any other suitable manner. The clean surface is then lightly treated with an acid solution, and the so called crystallized surface indicated at 2 is produced.

The surface so provided is coated with a transparent aniline color preferably by a lithographic press. The coating indicated at 3 being transparent, the markings of the plate surface, that is the crystallization, show through, and the color may be varied in accordance with the purpose for which the plate is to be used, and in accordance with the design which is to be printed thereon.

After the surface has been so prepared,

the design is impressed thereon. This is usually a lithographic process. A lithographic printing plate is prepared, and the design is lithographed in the usual manner, but in silhouette, so that selected portions of the design, as for instance the high lights are provided by the crystallized surface. This latter step is shown at 4 in the drawings, and it will be obvious from a consideration of the portion 4 of the plate that in the present instance the background is blocked out, leaving the high lights in the tinted crystallized surface.

The design is in the nature of silhouette, having the high lights without color, or open, and the shadows of opaque color, so that when impressed upon the crystallized surface the open parts of the design appear in said surface, said surface being blocked out to provide the shadows. The term silhouette or shadow outline is used, because a shadow or at least the heavy shadows are blocked out, while the high lights are open.

The design is of a character such that it will appear to the best advantage in the finished article. As for instance when circular boxes are to be made, the design will be circular to conform with the box.

Preferably the dimensions of the design are such that a margin of tinted crystallized surface will enclose the design, and when for instance the article to be made is a box top, the side wall of the top also will be of the tinted crystallized surface. If display matter such as printing is to appear on the article such matter is very conveniently produced by open printing, so that the letters or other display matter appear in the tinted crystallized surface.

After the design has been printed, a suitable blank is cut from the sheet, and formed into the article, the forming of the article being carried out in such manner as to conform with the design and emphasize the same. In box tops for instance the design may occupy a depressed portion in the top, encircled by a bead like frame.

I claim:

1. The method of decorating sheet metal, which consists in cleaning the surface with an alkali, treating the surface with an acid to provide a crystallized or galvanized effect, coating with a transparent color, and

impressing thereon an open design, so that selected parts thereof are formed by the tinted crystallized surface.

2. The method of decorating sheet metal, which consists in providing a surface thereof with a crystallized effect, coating with a transparent color, and impressing thereon a design wherein the shadows are in an opaque color.

10 3. As an article of manufacture, decorated sheet metal, with a crystallized transparent color coated surface having imprinted thereon an open design with selected parts thereof formed by the tinted crystallized background.

15 4. As an article of manufacture, decorated sheet metal with a crystallized transparent color coated surface having imprinted thereon a design wherein the shadows

20 are formed by an opaque color blocking out the crystallized tinted surface.

5. The method of decorating sheet metal, which consists in treating the surface thereof with acid to provide a crystallized effect, coating the crystallized surface with 25 a transparent aniline color, and imprinting on the coating a design wherein parts thereof are in an opaque color harmonizing with the color of the coating and blotting out said coating.

30 6. The method of decorating sheet metal having a crystallized surface effect, which consists in coating the surface with a transparent color, and imprinting on the coating a design wherein the shadows are in an 35 opaque color and the high lights open to display the crystallized surface.

Signed at Baltimore in the State of Maryland this 17th day of November, A. D. 1925.

MARTHA H. CONNOR.
